UNITED STATES PATENT OFFICE.

ROMUALD GRODZKI AND SIMEON IVANOFF, OF NEW YORK, N. Y.

RAILWAY-STATION INDICATOR.

1,125,515.

Specification of Letters Patent. Patented Jan. 19, 1915.

Application filed June 24, 1914. Serial No. 847,002.

To all whom it may concern:

Be it known that we, ROMUALD GRODZKI and SIMEON IVANOFF, both subjects of the Czar of Russia, and residents of the city of 5 New York, borough of Manhattan, in the county and State of New York, have invented a new and Improved Railway-Station Indicator, of which the following is a full, clear, and exact description:

Among the principal objects which the present invention has in view are: to provide an apparatus and means operatively connecting the same with the running gear of a vehicle, to announce the successive stations on a railroad; to provide manually-operative means for at will continuing, discontinuing, and reversing the operation of said apparatus; to provide an announcing ribbon or belt and means operatively associated therewith for relieving the same of strains, and for avoiding the misregistering thereof; and to provide means for winding and unwinding said ribbon, to compensate for the relative increase and decrease in diameter of the rolls for supporting said ribbon.

Drawings.—Figure 1 is a front elevation of an indicator of the character mentioned, constructed and arranged in accordance 30 with the present invention, and of the transmission mechanism operatively connecting the same with the running gear of a vehicle, the floor of the vehicle and the case containing the indicator mechanism being shown in section; Fig. 2 is a plan view of said indicator, the parts being shown on an enlarged scale, and the casing for containing the same being shown in section; Fig. 3 is a vertical section of the operating or driving shaft of the indicator, a starting mechanism therefor, and a fragment of the driving shaft thereof; Fig. 4 is a vertical section taken as on the line 4—4 in Fig. 2; Fig. 5 is a vertical cross section of the upper fragment of 45 the case, and portions of the driving and guiding mechanisms for the announcing ribbon carried therein; Fig. 6 is a detail sectional view taken on the line 6—6 in Fig. 3; Fig. 7 is a detail view showing a means connecting the clutch-shifting plungers.

Description.—As seen in the drawings, the ribbon 12 is provided at suitable intervals with markings or symbols indicating the stations of a railway for which said indicator 55 is provided. The ribbon 12 is alternately wound and unwound upon and from spools 13 and 14. The spools 13 and 14 are prefer-

ably mounted on driving shafts, having at the lower end bevel gear wheels 15 and 16. The gear wheels 15 and 16 are operatively 60 connected with gear wheels 17 and 18 mounted on tapered screw-threaded drums 19 and 20, respectively. The drums 19 and 20 are each supported by pivot posts 21 and 22, said posts being extended from the sides of 65 a case 23. Said posts and the drums 19 and 20 supported thereby are disposed in approximately the same horizontal plane, and said drums are reversely extended, the smaller ends of each of said drums being adjacent the wheels 17 and 18 mounted on said drums.

The spools 13 and 14 are supported by brackets 24 and 25, respectively, while the cores 26 and 27 of said spools are steadied 75 by the pivot posts 28, as best shown in Fig. 1 of the drawings. Intermediate the brackets 24 and 25, and on the plane therewith, is a cross rail 29, provided to support the driven rollers 30 and 31 and corresponding 80 idlers 32 and 33. As shown best in Fig. 2 of the drawings, said idlers are alined in a plane parallel to the vertical median plane of the case 23, and with a glass panel 34 at the inner end of a passage 35 opening at the 85 front of the case and extending inward to the vicinity of the ribbon 12, where the same crosses between the idlers 32 and 33.

It will be understood that the ribbon 12 is primarily moved by the rollers 30 and 31, 90 and that to this end, said rollers are provided with bevel gear wheels 36 and 37, as shown best in Figs. 2 and 4 of the drawings. The wheels 36 and 37 are of equal size, and are each operatively and permanently engaged by bevel gear wheels 38 and 39 mounted on a shaft 40, as seen best in Fig. 4 of the drawings. The shaft 40 is provided with fixed pulleys 41 and 42, to which is transmitted movement by the belts 43 and 44, the former of which as shown best in Fig. 4 of the drawings, is twisted, while the latter is straight. Said belts are permanently engaged by pulleys 45 and 46, respectively. The pulleys 45 and 46 are shown best in Fig. 105 3 of the drawings to be loosely mounted on sleeves 47 and 48, respectively.

The sleeves 47 and 48 constitute the main transmission elements of the machine, whereby the motive power for operating the 110 same is transmitted from a driving shaft 49. The driving shaft 49 is mounted vertically, and extends through a hollow pedestal 50 disposed as a fixture in a car structure. At

the lower end, the shaft extends below the floor of the car or vehicle, and is provided at the extremity with a bevel gear wheel 51, which is held in mesh with a companion gear wheel 52 on a countershaft 53. The countershaft 53 is supported in bearings 54 suspended from the under side of the floor of the car, and has fixedly mounted thereon a worm gear wheel 55, the teeth whereof 10 are meshed with a worm 56 on a transmission shaft 57. The shaft 57 has fixedly mounted thereon a second worm gear wheel 58, the teeth whereof mesh with the thread of a worm 59 on a transmission shaft 60. 15 The shaft 60 is suspended in bearings 61 pendent from the floor of the car or vehicle, as seen best in Fig. 1 of the drawings. The outer end of the shaft 60 is furnished with a sprocket wheel 62, which is operatively connected by means of a sprocket chain 63 with a relatively small sprocket wheel 64 on the carrying axle 65 of the car or vehicle.

The wheels 64 and 62, the worms 59 and 56, the wheels 58 and 55, the wheel 52 and 25 the wheel 51 all constitute a train of gears, arranged to relatively reduce the speed transmitted from the axle 65 to the shaft 49, to produce a relatively slow speed on the shaft 49 as compared to the speed of the 30 axle 65. It will be understood that the ratio may be largely varied by altering the relative sizes of any of the wheels constituting the chain above indicated.

The sleeves 47 and 48 are supported by, 35 and rotatively mounted upon plungers 66 and 67. The plungers 66 and 67 are non-rotatively mounted in the case 23, and are connected at the inner ends by a square loop 68, with which loop said plungers may be 40 optionally pivotally or rigidly connected. At the outer ends of each of the plungers, they are provided with push-heads 69 and 70, as best shown in Fig. 3 of the drawings.

The sleeves 47 and 48 have each rigidly 45 attached thereto, at the end thereof, bevel gear wheels 71 and 72. The gear wheels 71 and 72 are adapted to be engaged by a bevel gear wheel 73, which wheel is slidably mounted upon the upper end of the shaft 49, 50 being suitably splined or keyed thereto to rotate therewith. The hub of the wheel 73 is channeled to fit a block 74, by which said wheel is lifted or depressed. The block 74 normally rests on the thick portion 75 of a 55 tongue extended from the end of the thrust bar 76. The tongue is provided with a thin portion 77 connected with the thick portion by means of inclines 78. The inclines 78, as shown best in Fig. 6 of the drawings, are 60 disposed at opposite sides of a rectangular opening 104 formed in the tongue to straddle the shaft 49. The thrust bar 76 is furnished at the outer end thereof with a knob handle 79, provided to be manually engaged 65 for adjusting the bar 76. The tongue, at

the inner end of the bar 76, rests on a level member 80. From the sides of the block 74 extend pins 81, to which are secured springs 82. The springs 82 are anchored, as best shown in Fig. 4 of the drawings, to continuously exert a downward pull upon the block 74 and the wheel 73 connected therewith.

From the foregoing, it will be observed that when the operator grasps the handle 79 75 and withdraws the rod 76, the thin portion 77 of the tongue passes under the block 74. The block 74 and the wheel 73 connected therewith are then lowered by the springs 82, until the wheel 73 is disengaged from 80 the wheels 71 and 72. In this position, the indicator mechanism is at rest. Prior to engaging the wheels 71, 72 and 73, the operator presses on one of the heads 69 or 70 to adjust the clutches 83, 84, 85 and 86 to operate the pulleys 87, 88, 45, 89, 90 and 46, which pulleys and clutches are best seen in 85 Fig. 3 of the drawings.

As above stated, the pulleys 45 and 46 are operatively connected with the pulleys 41 90 and 42 on the shaft 40. When the plungers 66 and 67 are disposed as shown in Fig. 3 of the drawings, the clutch 84, fixedly mounted on the plunger 66 by a pin 91, operatively engages the pulley 45. By the same operation, the clutch 86 which is fixedly mounted on the plunger 67 by means of the pin 91 is moved out of engagement with the pulley 46. This arrangement insures the drive of the roller 30 to feed the ribbon 12 in the direction indicated by the arrows in Fig. 2 of the drawings. It will be understood that if the reverse drive of the ribbon 12 is desired, the push-head 70 is thrust inward to effect the engagement of the clutch 86 with the pulley 46, and the disengagement of the clutch 84 with the pulley 45.

The pulleys 87 and 88 and 89 and 90 are arranged in pairs, and are operatively connected by means of belts 92, 93, 94 and 95 110 with pulleys 96 and 97 and with pulleys 98 and 99. The belts 93 and 95 are reversed, being thereby arranged to transmit a reverse rotary direction to drums 100 and 101 upon which the pulleys 97 and 99 are 115 respectively mounted.

The drums 100 and 101 correspond in shape and construction with the drums 19 and 20, and are mounted directly beneath said drums 19 and 20, in paired relation 120 thereto but in reversed direction as far as the taper is concerned, that is, the small end of the drum 100 is disposed below the large end of the drum 19, and the small end of the drum 101 is disposed below the large 125 end of the drum 20. The drums 19, 20, 100 and 101 are similarly grooved or threaded. Each pair of drums is operatively connected by belts 102 and 103. The power driving the drums 19 and 20 is thus transmitted 130

through the drums 100 and 101. The drums 19 and 20, through their bevel wheels 17 and 18, respectively, operate the spools 13 and 14, and in the same relative rotary direction. 5 By coupling the drums 19 and 100 and 20 and 101 by the belts 102 and 103, it will be observed that the belts will be fed by the grooves in said drums to travel from one end thereof to the other, and in relatively 10 reverse directions lengthwise of the case 23.

From the foregoing, it will be seen that if the ribbon 12 is being driven in the direction indicated by Fig. 2 of the drawings, the belt 103 is moving toward the small end 15 of the drum 20 and toward the large end of the drum 101. The result of this action is that the rotation of the spool 14 is being gradually increased as the diameter of the wound ribbon 12 thereon is being gradually 20 decreased. In a similar manner, the belt 102 is being moved by the thrust on the drums 19 and 100 toward the large end of the drum 19 and the small end of the drum 100, thereby relatively diminishing the 25 transmitted speed of rotation of the spool 13. By this method, provision is made for the gradually increasing peripheral speed of the roll of ribbon 12 on one of said spools, and the correspondingly decreasing 30 peripheral speed of the roll on the other of said spools.

Claims:

1. An indicator as characterized, comprising a ribbon having disposed thereon the names of stations of a railroad, the intervals between said names corresponding with the intervals between the stations on said railroad; a plurality of winding spools for said ribbon, said spools being disposed in spaced 5 relation and at opposite sides of a view opening; a plurality of elongated tapered transmission drums, each of said drums being operatively connected with one of said spools to rotate the same, the connection between each drum and the corresponding spool being adjacent the smaller end of said drum; a plurality of correspondingly shaped driving drums, each disposed in parallel relation to one of said transmission 10 drums, said driving and transmission drums being relatively reversed; and a driving mechanism connecting each of said transmission drums and its companion driving drum for progressively increasing and diminishing the speed of said transmission 15 drums.

2. An indicator as characterized, comprising a ribbon having disposed thereon the names of stations of a railroad, the intervals between said names corresponding with the intervals between the stations on said railroad; a plurality of winding spools for said ribbon, said spools being disposed in spaced 20

relation and at opposite sides of a view opening; a plurality of elongated tapered transmission drums, each of said drums being operatively connected with one of said spools to rotate the same, the connection between each drum and the corresponding spool being adjacent the smaller end of said drum; a plurality of correspondingly shaped driving drums, each disposed in parallel relation to one of said transmission drums, said driving and transmission drums being relatively reversed; and a driving mechanism connecting each of said transmission drums and its companion driving drum for progressively increasing and diminishing the speed of said transmission 25 drums, said transmission drums and driving 30 drums operatively connected therewith, being relatively reversed in their connection with each of said spools.

3. A railway station indicator comprising a ribbon having serially disposed thereon the names of stations of a railroad, the intervals of the names on said ribbon corresponding with the intervals between the stations on said railroad; means operatively connected with the running gear of a vehicle 85 traveling on said railroad corresponding to the speed of said running gear, embodying oppositely-disposed spools for delivering and collecting said ribbon; and means interposed between said spools and the driving 90 mechanism therefor to vary the speed of said spools in correspondence with the variations of the diameter of the ribbon disposed on said spools.

4. A railway station indicator comprising a ribbon having serially disposed thereon the names of stations of a railroad, the intervals of the names on said ribbon corresponding with the intervals between the stations on said railroad; means operatively 100 connected with the running gear of a vehicle traveling on said railroad corresponding to the speed of said running gear, embodying oppositely-disposed spools, for delivering and collecting said ribbon and a plurality of 105 reversely-tapered driving drums, one of said drums being connected with one of said spools; a driving belt operatively connecting said drums; means for feeding said belt lengthwise of said drums; and manually- 110 controlled means for reversing the operation of said spools.

In testimony whereof we have signed our names to this specification in the presence of two subscribing witnesses.

ROMUALD GRODZKI.
SIMEON IVANOFF.
